CLAIM

The ornamental design for a separable tool box unit for the bed of a pickup truck, as shown and described.

DESCRIPTION

FIG. 1 is a front elevational view of the separable tool box unit for the bed of a pickup truck showing my new design; FIG. 2 is a rear elevational view thereof; FIG. 3 is a left side elevational view thereof; FIG. 4 is a right side elevational view thereof; FIG. 5 is a top plan view thereof; FIG. 6 is a bottom plan view thereof; and, FIG. 7 is a perspective view thereof in separated condition in position of use in the bed of a pickup truck which is shown in broken lines for illustrative purposes only and forms no part of the claimed design.
